UNITED STATES PATENT OFFICE.

HARRY C. LYONS, OF MOUNT VERNON, NEW YORK.

MEASURING FAUCET.

Application filed December 23, 1924. Serial No. 757,609.

While my improvements in the construction and operation of parts are applicable to measuring faucets generally, and for various other purposes, they are designed primarily 5 for embodiment in faucets to be used in the measuring and serving of cream, syrup, etc., of a viscous, semi-fluid character, especially cream of milk, which latter is particularly susceptible to discoloration by metallic 10 trition of parts with which it may be brought into contact, as where the valves of the faucet engage rotatively with their seats in the outlet and inlet ports, as heretofore. Another 15 object of my present invention, which is the result of years of experimental investigation in connection with measuring and dispensing faucets for use in conjunction with my sanitary milk dispensing means well known in the trade, is to facilitate the cleansing of all 20 parts of the faucet, and to simplify and cheapen the construction as well as the manipulation thereof, all as hereinafter fully set forth,—the invention consisting essentially 25 in the specific construction and arrangement of parts described and claimed herein, and a distinctive feature being the method and means employed for operating both the inlet and outlet valves.

In the accompanying drawings I illustrate 30 a practical embodiment of the essential features of my invention in a faucet of the character designated, although I do not limit myself to the identical form and construction of parts shown by way of exemplification, since 35 modifications may be made in minor details, and equivalent mechanical expedients resort- 40 ed to, with like results and without departing from the spirit and intent of my invention in this respect.

With this understanding:—

Fig. 1, represents a central longitudinal sectional view of a preferred form of my measuring faucet, showing the inlet valve open and the outlet valve closed;

Fig. 2, is a view like unto Fig. 1, showing the inlet valve closed and the outlet valve open;

Fig. 3, is a front end elevation, with the cap removed;

Fig. 4, is a transverse section taken upon plane of lines 4—4 Fig. 2.

In the preferred construction of my measuring faucet the head a , of the stem a' , of the inlet valve A, is formed with a duplex male 55 screw thread a^2 , of relatively steep pitch engaging with a correspondingly formed fe-

male screw thread b , (Fig. 2) in the body b' , of the outlet valve B, said valve body b' , being formed with a stem b^2 , having a rectangular end b^3 , for engagement with turning means, such as a handle b^4 , as indicated by dotted lines in Fig. 2, or equivalent mechanical expedient for imparting a partial turn to the valve B, considered in a unitary sense. The body b' , of the valve B, fits snugly in a cylindrical portion c , of the casing C, the conoidal outlet valve seat c' , being intermediate between said cylindrical portion of the casing C, and the measuring chamber c^2 , thereof, said measuring chamber terminating in the inlet valve seat c^3 . c^4 , is a vent in the casing C, for admitting air to replace the outlet through the spout c^5 , when the discharge valve B, is open.

The outer end of the casing C, is closed by a screw cap D, between which and cross studs b^5 , b^6 , on the valve stem b^2 , is interposed a spiral spring e, which tends constantly to press the outlet valve B, to its seat c' , as shown in Fig. 1 of the drawings, which view represents the normal co-relative positions of the parts, with the inlet valve A retracted from its seat c^3 .

This opening of the inlet valve A, to the position shown in Fig. 1, is effected only when the outlet valve B is seated, by an approximately half turn of the valve head b' , through the medium of the handle b^4 , thereby causing the female screw thread b , acting on the male screw thread a^2 , of the valve stem a' , to retract the valve A, from its seat c^3 , into the position shown in Fig. 1. The valve stem a' , screw thread a^2 and valve A are held against rotative movement by means of radial arms a^x , a^y , on the stem a' , (Fig. 4) the outer extremities of which engage with longitudinal grooves c^x , c^y , formed for the purpose in the side walls of the measuring chamber c^2 .

The head b' , of the valve B, being held seated normally by the spring e, it is obvious that the inlet valve A, may be seated or retracted by a partial rotation of said head b' , the pitch of the screws a^2 , and b , being sufficient for the purpose. Hence, when the inlet valve A is seated, a further turning movement imparted to the head b' , in the same direction which seated the inlet valve A, will force said head b' , and valve B, outward against the resistance of the spring e, into the position shown in Fig. 2, the seated inlet valve A, acting as the fulcrum or abutment to thus effect the opening of the outlet valve B, for

the discharge of the contents of the measuring chamber c^2 through the spout c^5 . It will thus be seen that the two valves are successively and alternately opened and closed by a simple operation of the handle.

A stop c^6 in the casing C limits the possible rotation of the valve head b' by contact with one end of the radial stud b^5 . The opposite end of said stud is shortened so as to clear the stop c^6 , thus making it possible to rotate said valve head b' nearly one complete revolution.

It will be readily understood that the operative parts shown may be easily removed from the casing for cleansing purposes, and as readily reassembled for use. This result is attained by making the inlet valve seat c^3 , of less diameter than the measuring chamber c^2 , and the outlet valve seat c' , of greater diameter than that of the said measuring chamber c^2 , so that the valves and connections may be inserted or removed intact.

It is to be understood that I do not limit myself to the duplex arrangement of screw threads shown, and that the latter may be alternated as related to each other with like results.

What I claim as my invention and desire to secure by Letters Patent, is:—

1. In a device of the character described, two valves, seats for said valves, one of said valves being rotatable, means for holding the other of said valves against rotation, screw-thread means directly connecting said valves and adapted when said rotatable valve is rotated to cause said valves to be successively and alternately moved axially.

2. In a measuring device, a casing having a measuring chamber, an inlet valve and seat,

an outlet valve and seat, means for preventing rotation of one of said valves, means for rotating the other of said valves, and positive and directly operating means of connection between said valves, adapted to move one of said valves axially to its seated position when the other of said valves is rotated and when said valve is seated and the other valve further rotated to cause said last-mentioned valve to be moved relatively to its seat.

3. In a measuring device, a casing, inlet and outlet valves for said casing, positive and directly operating means for connecting said valves and causing relative longitudinal movement between said valves upon rotation of one of said valves, and a spring for holding one of said valves against longitudinal movement while the other valve is being moved.

4. In a measuring device, a casing having a measuring chamber, inlet and outlet valves for said chamber, said valves having a positive screw-threaded connection with each other permitting one of said valves to be rotated, means for holding the other of said valves against rotation, and means for rotating one of said valves and causing each of said valves to be moved alternately and axially relatively to each other.

5. In a measuring device, a casing having a measuring chamber, inlet and outlet valves for said chamber, means for holding one of said valves against rotation, means for rotating the other of said valves, and means forming a positive and direct connection between said valves and operated by the rotation of said rotary valve to cause successive and alternate axial movement of said valves.

HARRY C. LYONS.
